FIG. 1.

FIG. 2.

UNITED STATES PATENT OFFICE

2,425,790

BED SWITCH

Roland A. Fletcher, San Diego, Calif.

Application January 12, 1946, Serial No. 640,822

5 Claims. (Cl. 200—85)

1

This invention relates to weight-actuated switches and is particularly applicable for use under a leg of a bed for turning on a night lamp in response to the lessening of the weight on the leg when an occupant of the bed gets up.

An object of the invention is to provide a compact and reliable switch structure so shaped that the actuating member thereof can be placed under one leg of a bed without raising the leg materially above the level of the floor.

Another object is to provide a weight-actuated switch structure that can be adjusted to function under beds of different weights and for people of different weights.

Another object is to provide a compact and rugged unit consisting of a weight-actuated switch and a lamp controlled thereby which unit can be placed partially under and partially adjacent the leg of a bed for providing illumination when an occupant of the bed gets up.

Other more specific objects and features of the invention will become apparent from the description to follow of a particular embodiment of the invention as illustrated in the drawing, in which:

Fig. 1 is a longitudinal, vertical section through a switch unit in accordance with the invention;

Fig. 2 is a view partially in plan and partially in section, the section being taken along the line II—II of Fig. 1;

Fig. 3 is a cross-section taken along the line III—III in Fig. 1; and

Fig. 4 is a schematic diagram showing the electrical circuit of the device.

Referring first to Figs. 1, 2 and 3, the device shown comprises a housing 10 containing a switch for controlling a lamp 11 which may be mounted on top of the housing, while projecting from one side of the housing 10 is a member 12 adapted to be placed under a leg 13 of a bed and to respond to variations in the weight of the leg 13 to actuate the switch and turn the lamp on and off.

The housing 10 may consist of a metal stamping having end-walls 14 and 15, side-walls 16 and 17, and a top-wall 18, all formed in one piece. The bottom-wall 19 is formed by a separate piece of metal and extends beyond the end-wall 15 as a strip 20 that is doubled back on itself as indicated at 21 and extended almost back to the end-wall 15 to constitute the member 12. The upper portion 22 of this strip may be indented near its middle as indicated at 23 to receive the foot of the leg 13 and prevent the foot from slipping off the member 12.

The member 12 is preferably formed of relatively heavy, elastic metal so that it has substan-

2

tial resistance to bending by the weight of the leg 13. However, it is usually undesirable to make the number 12 sufficiently stiff to fully support the weight, and it is preferably reinforced by a helical compression spring 24, which is interposed between the sections 20 and 22 of member 12 and is centered by the depressed portion 23 of the section 22.

The end of the section 22 adjacent the end-wall 15 of the housing 10 is provided with a switch-actuating tongue 25 of insulating material, which extends through a slot 26 in the end-wall 15, into the housing 10. The tongue 25 may be secured to section 22 by rivets 27.

The contact mechanism within the housing 10 comprises a pair of leaf springs 28 and 29 positioned one above the other and both supported at one end. Thus the lower leaf spring 29 rests upon an insulating block 30 which lies upon the bottom-wall 19. A second block of insulating material 31 rests upon the spring 29 and separates it from the spring 28. A third block 32 of insulating material rests upon the spring 28 and extends upwardly through the top-wall 18 of the housing 10 and is provided with a shoulder 321 which engages the wall 18. A screw 33 extends through an aperture provided therefor in the bottom-wall 19 and is threaded into the insulating block 32. When this screw 33 is tightened it compresses the pile consisted of the block 30, the spring 29, the block 31, the spring 28, and the block 32 together, and also holds the right end of the bottom-wall 19 against the housing 10. An insulating bushing 34 surrounds the screw 33 within the blocks 30 and 31, to insulate the screw from the contact springs 28 and 29.

As best shown in Fig. 3, the block 32, in addition to functioning as a structural member to support the leaf springs 28 and 29, also functions as an electrical receptacle. Thus it has a pair of slots 35 and 36 which open through its upper surface into recesses 37 and 38, in which spring contacts 39 and 40 are located.

The device is adapted to be energized over a two-conductor lamp cord from a common source of lighting current, and to this end a pair of conductors 41 and 42 are shown entering the end-wall 14 of the housing through an insulating bushing 43 positioned in an aperture in the wall 14. One of these conductors, 41, is connected directly to the lower leaf spring 29, and the other conductor, 42, is connected directly to the receptacle contact 40. The other receptacle contact 39 is connected by a wire 45 (Fig. 3) to the other leaf spring 28. It will be observed, therefore, that,

3

when the contact springs 28 and 29 are closed, a circuit is completed from the supply conductors 41 and 42 to the two contacts 39 and 40 of the receptacle, and a lamp connected to the receptacle will be lighted.

As shown in Fig. 1 the lamp 11 is screwed into a standard form of receptacle 41 which has a pair of prongs extending through the slots 35 and 36 in the receptacle and making electrical contact with the contacts 39 and 40.

If it is desired to have the lamp in some other location, the receptacle 41 can be removed, and an extension cord plugged in.

The contact springs 28 and 29 are provided near their outer ends with contacts 281 and 291 respectively. The lower contact spring 29 is extended beyond the end of the spring 28 and is adapted to be engaged by the end of the insulating tongue 25. The upper spring 28 normally bears against an insulating tip 50 on the lower end of a screw 51 which is threaded through the top-wall 18 of the housing and is provided with a handle 52 on its upper end.

The device functions as follows:

When the leg 13 of the bed which is to control the switch is rested in the recess 23 in the upper section 22 of the member 12, the leg depresses the tongue 25 to a pre-determined extent, dependent upon the weight of the bed. When the bed is not occupied, the contacts 281 and 291 should be closed, but they should be open when a person is in the bed. Adjustment to provide for the indicated operation is readily obtained by turning the adjusting screw 51, while the bed is empty, until the contacts 281 and 291 are just closed, as indicated by lighting of the lamp 11. With this adjustment, any additional weight imposed on the leg 13, as by a person getting into bed, is sufficient to break the contacts and extinguish the lamp. However, should the person leave the bed at any time during the night the reduction in the weight on the leg 13 permits the tongue 25 to move upwardly sufficient to again close the contacts 281 and 291 and light the lamp 11.

The arrangement has the practical advantage of providing an automatic night lamp which always lights in response to an occupant of the bed leaving it, without the necessity of the occupant groping around in the dark to find a light switch.

By means of the adjustment screw 51, the switch can be adjusted to function reliably regardless of the weight of the bed with which it is used and regardless of the weight of the occupant of the bed. Furthermore, if there is more than one occupant of the bed, the switch can be adjusted to light the lamp in response to rising of only one of the occupants.

A particular advantage of the structure is that it provides a rugged and reliable spring mechanism for supporting the weight of the leg, which structure is compact vertically so that it does not lift the leg high off the floor. The elevation of the leg by the device is sufficiently small to be permissible without correspondingly raising the other three legs off the floor. However, if desired, small supports of the same height as the spring section 22 may be placed under the other legs of the bed to maintain all four corners of the bed at the same level.

Although for the purpose of explaining the invention, a particular embodiment thereof has been described in substantial detail, various departures from the exact construction disclosed and described can be made without departing

4

from the invention, and the latter is to be limited only to the extent set forth in the appended claims.

I claim:

- 5 1. A device of the type described comprising: a casing defining an enclosure and consisting of a bottom-wall and separate cover means constituting side and top walls, said bottom-wall extending laterally beyond said cover member on one side thereof; the extended portion of said bottom-wall being folded back on itself and having a free end extended toward said cover member at a level below the top of said cover member, switch means in said casing; and means on said free end for actuating said switch means.
- 10 2. A device of the type described comprising: a casing defining an enclosure having an opening in one side thereof; a base member extending laterally from the bottom of said casing on said one side thereof; a weight-supporting vertically deflectable member positioned above said base member and secured at its outer end to the outer end of said base member; the inner end of said deflectable member extending through said opening into said casing; and switch means in said casing operable in response to vertical movement of the inner end of said deflectable member; said switch means comprising a pair of leaf spring members positioned one above the other and having normally closed electrical contacts; means coupling the lower spring member to said inner end of the deflectable member whereby downward movement of the latter moves said lower spring member downwardly; and means for adjusting the upper spring member vertically to vary the vertical position of said deflectable member at which said contacts break.
- 15 3. A device of the type described comprising: a casing defining an enclosure having an opening in one side thereof; a base member extending laterally from the bottom of said casing on said one side thereof; a weight-supporting vertically deflectable member positioned above said base member and secured at its outer end to the outer end of said base member; the inner end of said deflectable member extending through said opening into said casing; and switch means in said casing operable in response to vertical movement of the inner end of said deflectable member; said switch means comprising a pair of leaf spring members positioned one above the other and having normally closed electrical contacts; means coupling the lower spring member to said inner end of the deflectable member whereby downward movement of the latter moves said lower spring member downwardly; and an adjusting screw threaded through the wall of said casing and contacting the upper spring member for vertically adjusting said upper spring member to vary the vertical position of said deflectable member at which said contacts break.
- 20 4. A device of the type described comprising: a casing defining an enclosure and consisting of a bottom wall and separate cover means constituting side and top walls, said bottom wall extending laterally beyond said cover member on one side thereof; the extended portion of said bottom wall being folded back on itself and having a free end extended toward said cover member at a level below the top of said cover member; switch means in said casing; means on said free end for actuating said switch means; and means for adjusting said switch means to vary the movement of said free end required to actuate
- 25 75 said switch means.

5. A switch responsive to occupation of a bed comprising: deflectable spring means adapted to be interposed between the leg of a bed and the floor and deflectable in response to variations in weight on the bed; a pair of normally closed electrical contact members; means for shifting one of said contact members in circuit-opening direction in response to the deflection of said spring means resulting from an increase in weight on said bed; and means for varying the 10 magnitude of said deflection required to open said contact members.
